(57) **CLAIM**

The ornamental design for headwear, as shown and described.

DESCRIPTION

FIG. 1 is a front elevation view of headwear, showing our new design, in a first condition of use, the first condition of use having a transparent visor.

FIG. 2 is a left elevation view of the headwear, in the first condition of use.

FIG. 3 is a right elevation view of the headwear, in the first condition of use.

FIG. 4 is a top plan view of the headwear, in the first condition of use.

FIG. 5 is a bottom plan view of the headwear, in the first condition of use.

FIG. 6 is a rear elevation view of the headwear, in the first condition of use.

FIG. 7 is a front-right-top perspective view of the headwear, in the first condition of use.

FIG. 8 is a front-left-top perspective view of the headwear, in the first condition of use.

FIG. 9 is a front-right-bottom perspective view of the headwear, in the first condition of use.

FIG. 10 is a front-left-bottom perspective view of the headwear, in the first condition of use.

FIG. 11 is a front elevation view of headwear, showing our new design, in a second condition of use, the second condition of use having no visor.

FIG. 12 is a left elevation view of the headwear, in the second condition of use.

FIG. 13 is a right elevation view of the headwear, in the second condition of use.

FIG. 14 is a top plan view of the headwear, in the second condition of use.

FIG. 15 is a bottom plan view of the headwear, in the second condition of use.

FIG. 16 is a rear elevation view of the headwear, in the second condition of use.

FIG. 17 is a front-right-top perspective view of the headwear, in the second condition of use.

FIG. 18 is a front-left-top perspective view of the headwear, in the second condition of use.

FIG. 19 is a front-right-bottom perspective view of the headwear, in the second condition of use; and,

FIG. 20 is a front-left-bottom perspective view of the headwear, in the second condition of use.

Subject matter shown in broken lines is environmental and forms no part of the claimed design. For example, the interior portions of the bottom plan views in FIGS. 5 and 15

(Continued)

are shown in broken lines and form no part of the claimed design. The shade lines show surface contour and not surface ornamentation.
